BUNDLE TIE

William Robert Evans, Hershey, Pa., assignor to AMP
Incorporated, Harrisburg, Pa.

Filed Apr. 10, 1968, Ser. No. 11,447

Term of patent 14 years

Int. Cl. D9—08

U.S. Cl. D9—252

I claim:

The ornamental design for a bundle tie, substantially as shown and described.
